UNITED STATES PATENT OFFICE.

HORACE L. KENT, OF BROOKLYN, NEW YORK, ASSIGNOR TO GEORGE H. FRASER, OF SAME PLACE.

PULVERIZING-MILL.

SPECIFICATION forming part of Letters Patent No. 673,856, dated May 7, 1901.

Application filed February 8, 1898. Serial No. 669,615. (No model.)

To all whom it may concern:

Be it known that I, HORACE L. KENT, a citizen of the United States, residing in Brooklyn, in the county of Kings, city and State of New York, have invented certain new and useful Improvements in Pulverizing-Mills, of which the following is a specification.

This invention relates to mills for crushing, granulating, or pulverizing rock, quartz, ores, and other materials.

It relates to that class of mills in which the material is crushed between the interior of a revolving ring and the exterior of a roll within said ring.

According to this invention the crushing-ring is a free ring yieldingly supported by one or more crushing-rolls, which it encircles. According to the preferred construction a plurality of rolls (preferably three) is employed, the rolls being pressed outwardly against the ring by springs to generate the requisite crushing pressure. The rolls not only uphold the weight of the ring, but also yieldingly support it against the crushing pressure. Thus the pressure exerted by one roll against the inner face of the ring is transmitted through the ring to the other roll, (or rolls,) so that the crushing pressure is distributed between the rolls. In the preferred arrangement with three rolls the uppermost roll is placed within the upper side of the ring and serves to carry the weight of the ring and to revolve it, while the two lower rolls are pressed by their springs outwardly against the ring to generate the requisite crushing pressure, this pressure being substantially equalized by the yielding or displacement of the ring, which assumes such position as to establish equilibrium between the forces acting upon it. The rolls and ring are inclosed in a suitable casing, and means is provided for feeding the material into this casing and between one of the rolls and the ring.

Figure 1 of the accompanying drawings is a side elevation of this mill, being partly broken away to show the interior construction and partly in vertical mid-section. Fig. 2 is an end elevation, the right-hand half being in vertical mid-section and the lower part of the left-hand half being also in section.

Fig. 3 is an elevation of the feeder, which is only partly shown in Fig. 2. Fig. 4 is a vertical mid-section of the feeder. Figs. 5 and 6 are sections showing details of the bearing equipments. Fig. 7 is a diagram of the working parts of the mill. Figs. 8, 9, and 10 are similar diagrams showing modifications. Fig. 11 is a fragmentary section answering to Fig. 5.

Referring to the drawings, and especially to Figs. 1 and 2, A is the inclosing casing, B is the revolving crushing-ring, and C C are the crushing-rolls within the ring, preferably three in number, as shown. The ring B is supported wholly upon the three rolls C C, which latter are pressed outwardly against the ring by means of suitable springs. The rolls are fixed on shafts D D, which extend horizontally out through openings in the casing and are held in bearings E E on opposite sides of the casing. These bearings are fixed or mounted on movable guiding frames or slides F F, the principal purpose of which is to connect together the two bearings of each shaft, hold them in alignment, and provide for transmitting the spring-pressure to them. These frames may be variously constructed; but I prefer the construction shown, in which the frames are constructed as slides, each one consisting of two parallel longitudinally-sliding bars a a, the inner ends of which carry the bearings and the outer ends of which are fixed in a cross-head b, extending across outside of the casing and receiving at its middle the thrust of a spring S, by which the pressure is imparted for thrusting the roll against the ring. Preferably the middle of the cross-head b is formed with a socket c, into which one end of said spring projects, while the other end reacts against the exterior of the casing A. The stress of the spring is adjusted by means of a screw d, which screws through the cross-head, and its inner end bears upon a disk e, against which the spring presses, so that by forcing this disk in by the screw the spring may be more or less compressed. A set-nut locks the screw in place. Preferably all three of the rolls C are supported in like manner by bearings E and frame F, all of the same construction. The sliding bars a a move in any suitable slide-

ways or bearings formed on the casing, being preferably tubular bearings *g g*, shown as cast integrally with the casing.

The ring *B* is revolved solely by frictional contact with the rolls. Power may be applied to one, two, or all of the rolls, one being sufficient. I prefer to apply power to the shaft of the upper roll, as thereby the weight of the ring which is carried by this roll is utilized to impart the necessary driving traction. The speed must be sufficiently high to cause the material fed against the ring to be carried around with it centrifugally. To accomplish this, the ring, if of about thirty inches internal diameter, should have a minimum speed on its inner face of about three hundred and fifty feet per minute.

The casing *A* may be of any suitable shape or construction adapted to inclose the rolls and give support for the frames *F*, carrying the roll-shafts. The construction shown is preferred, the casing being cast in two parts divided horizontally at the middle, so that the upper half can be disconnected and lifted off to enable the ring to be removed.

The revolving ring *B* is closely embraced on opposite sides between stationary internal projections within the casing, preferably annular, so as to leave only narrow spaces *h*, Fig. 2, on opposite sides of the ring sufficiently wide to permit the escape of granulated or pulverized material, while preventing passage of any material that has not yet been crushed. As there is considerable wear against these fixed annular surfaces, it is preferable not to make them integral with the casing, and for this purpose I construct them as separate cheek-pieces or fixed rings *H H*, preferably divided in the same plane as the casing, which are fastened in the casing by screws *i i* at intervals or otherwise, and which are preferably cut away at the bottom (wholly or partly) to form openings *j j* for the more ready discharge of the crushed or pulverized material.

The material to be crushed is fed through the casing into the interior of the ring *B* and onto the descending side of one of the rolls *C*, so that the descent of the material will draw it in between the mutually-approaching faces of the ring and roll. I prefer to feed in simultaneously at both sides, but one side will suffice. The material is deposited in a hopper *G*, (shown in Figs. 1 and 3,) which branches at its bottom into two chutes *k k*, which terminate over upright chutes *I I*, formed on the opposite sides of the casing *A*. These chutes extend down outside the casing proper and terminate each with a bottom incline *l*, Fig. 2, which directs the material through an opening *m* in the casing and, throwing it across the stationary ring *H*, discharges it within the revolving ring.

To prevent the escape of dust through the feeding-chutes and hopper, I prefer to provide the hopper with dust-retaining doors *n*, the pivotal rods of which carry on the out-

side weighted arms *n'*, so that the doors tend to remain closed in the horizontal position, as shown in Fig. 1. When, however, a sufficient weight of material is fed into the hopper, these doors yield and swing downwardly, dumping the material down the chutes, and may remain open, as shown in Fig. 4, as long as the material is feeding in, afterward immediately closing to prevent escape of dust.

To provide for a uniform feed readily adjustable to the requirements of different materials and to different rates of feed, I provide the mill by preference with the construction of feeder shown in Figs. 1, 3, and 4. This consists of a receiving-hopper *J*, fixedly supported on brackets *J'*, with a vibrating chute or shaker *K*, freely suspended beneath it, and an agitator for this chute consisting of a cam *p*, carried on a revolving shaft *L*, this shaft being driven in any suitable manner—as, for example, by pulleys *q*, belted, as in Fig. 2, to pulleys *r* on the driving-shaft. The shaker *K* has side flanges which inclose the lower part of the hopper *J*, and it is hung from the hopper by three adjustable screws or bolts, two of which, *s s*, are arranged at the opposite sides, while a third, *t*, is arranged at the back. These bolts are so adjusted that the shaker is struck and slightly lifted at each revolution by the cam *p*, so as to impart to it a frequent jarring or vibratory movement. The extent to which it is lifted at each movement may be determined by adjusting-bolts *s s*. The rapidity of movement may be governed in two ways, first, by varying the speed of the shaft *L* by running its driving-belt on one or other of the pairs of pulleys *q r*, and, second, by adjusting the inclination of the shaker, which is effected by an adjustment of the bolt *t*. The shaker is shown at its steepest inclination in Fig. 1, adapted for giving the most rapid feed, and in Fig. 4 is shown lowered to more nearly a level position for giving a slower feed. The feed may also be adjusted by means of a slide *M*, movable in the hopper *J*, to more or less cover the front outlet thereof.

I provide means for protecting the journal-bearings *E E* against admission of dust or loss of oil. The outer ends of the journals of the shafts *D* (except the driving-shaft) are inclosed by means of caps *u u*, formed in halves and fastened by screws to the opposite halves of the bearings. To prevent end thrust of the shafts, each is provided with a thrust-collar *v*. The cap *u* is made large enough to freely inclose this collar, as shown in Fig. 5. It thus prevents dust or grit working into the bearing and prevents the escape of oil. At the opposite end of each bearing next to the casing *A*, I provide a dust-excluding packing-box *P*. (Shown in Figs. 5 and 6.) This consists of a casing made in halves and fastened by screws to the respective halves of the bearing *E* open at top, so that waste or other fibrous material may be packed into it in order to closely embrace the shaft and prevent any

dust or grit working along the shaft into the bearing. The subdivisions in the caps *u* and boxes *P* are made in the same planes as those of the respective bearings *E*.

- 5 The casing *A* is constructed with slots or openings suitably arranged for facilitating, assembling, or dismounting the machine. The top half of the casing has an upright slot *w* extending from the shaft *D* to the joint between the sections, so that when the upper half is to be lifted off from the lower the upper shaft *D* may be lowered through said slot. The lower half of the casing is provided with angular or curved slots *w'*, through which, the upper half being removed, either of the lower shafts *D* may be lifted out. These slots may be normally closed by thin plates or sheets of metal, leather, &c., to prevent escape of dust from the interior.
- 20 It is characteristic of my invention that the ring *B* is a loose or free ring supported solely by one or more crushing-rolls, which it encircles, and that these rolls turn upon axes which are substantially stationary as distinguished from axes which revolve around a main axis with a planetary motion. The ring is thus cushioned upon the springs *S S*, which press against these rolls, so that when any hard material enters between the ring and one of the rolls both the ring and roll may yield, the roll yielding by compressing its spring and the ring being displaced against the other rolls and compressing their springs. The ring is made concave in cross-section on its inner face, and the rolls are made with convex faces conforming thereto, so that the ring tends to run centrally upon the rolls; but in case any thick material enters upon one side it may be thrust sidewise until it strikes one of the fixed rings *H*. The ring being cushioned by the spring-mounted rolls, the machine runs quietly and with the minimum of jar and vibration. I prefer to employ three rolls, as already described and as shown in the diagram Fig. 7. My invention is not, however, limited to three rolls, being applicable with a greater or less number. In Fig. 8 I have shown four rolls, all being pressed outward in the direction of the radiating arrows. In Fig. 9 I have shown two rolls at diametrically opposite points. In all these constructions the crushing pressure is not dependent upon the weight of the ring, but is determined by an adjustment of the stress of the cushioning-springs. In the construction shown in Figs. 1 and 2 this adjustment is effected by means of the screws *d d*. By means of these screws the pressure of each lower roll against the ring may be varied from zero up to any desired limit—say, for example, twenty thousand pounds. The springs should be adjusted equally (except to the extent that the weight of the ring adds to the stress of the upper spring) in order to preserve the ring in the center of the casing. Practical use of this mill has demonstrated that by varying the adjustment of the three springs the mill can be

used as a granulator, working as coarse as an eight-mesh screen or as a pulverizer up to a fineness of two hundred mesh.

In Fig. 10 I have shown a modification in which the weight of the ring is alone relied upon to give the crushing pressure, the ring being supported on only one crushing-roll *C*, arranged at its upper side and cushioned on a spring *S*, the construction being the same as if the two lower rolls and their accessories in Figs. 1 and 2 were removed. In such construction the ring will require to be guided either by mounting guide-rolls *y y* (shown in dotted lines) exterior to the ring to prevent its swaying too far to either side, or by mounting similar rolls within the ring in the positions approximately of the two lower rolls in Figs. 1 and 2, or by mounting a single combined guiding and crushing roll in the position shown at *C'* in Fig. 10. The material entering at the opening *m* falls upon the inner surface of the ring, is carried around centrifugally, and is crushed between the ring and the roll *C* with a pressure depending upon the weight of the ring. This construction is not recommended, as the ring is not adequately supported and the crushing pressure is not adjustable; but it has nevertheless the advantage peculiar to my invention that the ring is a free ring, supported and driven by a crushing-roll which it encircles and which revolves on a stationary axis and which is spring-mounted, so as to cushion the revolving ring.

Fig. 11 shows a further improvement in the means for excluding dust from the bearings, preferred for many purposes over that shown in Fig. 5. The packing-box *P* is removed somewhat farther from the bearing, and between is a water-chamber *Q*, inclosing the shaft and having water inlet and outlet pipes *x* and *x'*, by which a small stream of water is caused to flow around the shaft to cool it in case the mill is used for grinding hot material and to wash off any grit that may have worked its way through the packing-box *P*. The pipes *x* are connected by sections of flexible hose with a source of water, and the pipes *x'* lead to any suitable waste. The water-chamber *Q* may or may not communicate with the packing-box *P*.

I have shown in Fig. 2, in dotted lines, one means of supporting the mill on beams of wood and also the application of a screw-conveyer *z* beneath the open bottom of the casing to carry away the powdered material.

It is an important feature of my invention that the revolving ring being supported by an internal crushing-roll at its upper side receives at one or more lower points the outward pressure of one or more additional crushing-rolls, which are mounted in yielding bearings and pressed against the ring by suitable yielding means, such as, preferably, by springs. Preferably a single upper roll supports the weight of the ring, while two lower rolls press yieldingly both down-

wardly and laterally against its inner surface at points suitably located beneath its horizontal diameter; but this arrangement may, as indicated, be varied without departing from my invention. By the outward pressure of such lower roll or rolls against the ring a crushing pressure greater than and independent of that due to the weight of the ring alone is made available.

10. In operating on hard materials it is necessary to provide a heavier crushing pressure than for relatively soft materials, and hence the pressure of the rolls is increased by setting in their adjusting-screws. The mill is 15 not rendered inoperative if the screws be set in so far as to close the springs together, so as to practically eliminate their elasticity, but its capacity is materially reduced. The 20 capability of such adjustment is, however, advantageous, as it enables the mill to be adapted for pulverizing to extreme fineness when required.

I claim as my invention the following-defined novel features, substantially as hereinbefore specified, namely:

1. A pulverizing-mill comprising in combination a revolving ring and a spring-mounted crushing-roll turning on a substantially stationary axis, arranged within and supporting 30 said ring, whereby the ring is free to yield and is cushioned on its supporting-roll.

2. A pulverizing-mill comprising in combination a revolving ring and a plurality of rolls within said ring, turning on substantially 35 stationary axes, one of said rolls supporting the ring, and a spring arranged to press said roll outwardly against the ring, whereby the ring is cushioned on said roll.

3. A pulverizing-mill comprising in combination a revolving ring and a plurality of rolls within said ring and supporting the latter, and springs arranged to resist the inward displacement of said rolls to thereby cushion the rolls.

4. A pulverizing-mill comprising in combination a plurality of crushing-rolls turning on substantially stationary axes, a revolving ring encircling and supported by said rolls, and means for causing the rolls to hug the 50 ring thus generating a crushing pressure between the rolls and ring independent of the weight of the ring.

5. A pulverizing-mill comprising in combination a plurality of crushing-rolls and their 55 shafts turning on substantially stationary axes, a revolving ring encircling and supported by said rolls, movable bearings for said shafts, springs for forcing said bearings outwardly to press the rolls against the ring, and means for adjusting the tension of said springs.

6. A pulverizing-mill comprising a revolving ring, combined with three crushing-rolls within and supporting said ring, and means 65 for pressing them outwardly against the ring, whereby the ring is yieldingly supported at three points.

7. A pulverizing-mill comprising a plurality of crushing-rolls, a free revolving ring encircling and supported solely by said rolls, the inner face of said ring being concave in cross-section and the outer faces of said rolls being convex and conforming thereto, and yielding means for forcing the rolls outwardly against the ring, whereby the ring is centered and held against lateral displacement.

8. The combination of a revolving ring, a crushing-roll within and supporting said ring, turning on a substantially stationary axis, a casing inclosing said roll and ring, bearings 80 for the shaft of said roll on opposite sides of said casing, a movable frame for said bearings extending on opposite sides of the casing for holding the bearings in alinement, and a spring applied to such frame for pressing 85 the bearings outwardly, whereby the roll is yieldingly mounted.

9. The combination of a plurality of crushing-rolls and their shafts, turning on substantially stationary axes, a revolving ring encircling and supported by said rolls, the bearings for said shafts, and a movable frame uniting the opposite bearings of one shaft to hold them in alinement.

10. The combination with a plurality of 95 crushing-rolls and their shafts, turning on substantially stationary axes, a revolving ring encircling said rolls, a casing inclosing said rolls and ring, bearings for the roll-shafts on opposite sides of said casing, a sliding frame 100 for the bearings of one such shaft extending on opposite sides of the casing for holding the bearings in alinement, slideways formed on said casing for said frame, and a spring applied to said frame for pressing its bearings 105 outwardly.

11. The combination of a laterally-yielding revolving ring, a plurality of crushing-rolls within and supporting said ring, a casing inclosing said rolls and ring, and fixed rings 110 within said casing on opposite sides of and normally slightly out of contact with said ring, whereby narrow spaces are left between the revolving ring and fixed rings through which the pulverized material may escape, 115 but preventing the escape of the uncrushed material, and constructed with outlet-openings formed in said fixed rings at their lower sides for facilitating escape of the pulverized material.

12. The combination of a revolving crushing-ring and a plurality of crushing-rolls within and supporting said ring, one of said rolls being arranged at the top and beneath the upper side of the ring, shafts on which said rolls are mounted, spring-pressed yielding bearings for said shafts, and driving means applied to the shaft of said upper roll, whereby the weight of the ring and the tension of the lower rolls are utilized to impart the traction for driving the ring.

13. The combination of a revolving ring, a crushing-roll and its shaft within said ring, a casing inclosing the ring and roll, bearings for

5 said shaft outside the casing, a frame F connecting said bearings, comprising parallel bars *a* sliding in guideways on the casing, a cross-head *b*, and a spring reacting against the casing and pressing outwardly against said cross-head to draw the roll toward the spring and thereby press it against said ring.

14. The combination of a revolving ring, a crushing-roll and its shaft within said ring, a 10 casing inclosing the ring and roll, bearings for said shaft outside the casing, a frame connecting said bearings comprising parallel side portions on opposite sides of the casing, and a cross-head joining them, a spring reacting 15 against the casing and pressing outwardly against said cross-head, and means for adjusting the tension of said spring consisting of a screw working through said cross-head and engaging the end of the spring.

20 15. The combination of a plurality of crushing-rolls and their shafts, a revolving ring encircling and supported by said rolls, a casing divided horizontally into an upper and lower section, the shafts of said rolls passing out 25 through the respective sections of said casing, and said casing formed with slots where said shafts pass through it, which slots extend to the subdivision of said casing to facilitate the removal of the shafts from the divided 30 casing.

35 16. The combination with a revolving crushing-ring, free to move axially and radially, of a plurality of crushing-rolls within and supporting said ring, said ring being internally concave in cross-section and said rolls externally convex, and means for pressing said rolls relatively outward, whereby they resist axial displacement of the ring.

40 17. The combination with a revolving crushing-ring, free to move axially and radially, of three crushing-rolls within and supporting said ring, said ring being internally concave in cross-section and said rolls externally convex, and means for pressing said rolls relatively outward, whereby they center the ring upon them and resist axial displacement thereof.

45 18. The combination with a revolving crushing-ring, of a plurality of crushing-rolls within 50 and encircled by said ring, one of said rolls being near the top of the ring and supporting the latter, and another of said rolls being near the bottom of the ring and pressing downwardly on the latter, and a yielding bearing 55 for the latter roll, and means for driving said ring, whereby both the weight of the ring and the downward pressure of the lower roll are utilized as crushing forces.

60 19. The combination with a revolving crushing-ring, of a plurality of crushing-rolls within 65 and encircled by said ring, one of said rolls being near the top of the ring and supporting it, and another of said rolls being near the bottom of the ring and pressing outwardly against its inner face, a yielding bearing for the latter roll, and means pressing said roll

outwardly against the ring, and means for driving the ring.

20. The combination with a revolving ring 70 movable both laterally and longitudinally of its axis, of a revolving roll within and encircled by said ring and supporting the latter near the top of the inner periphery of the ring, said roll movable laterally of its axis and yieldingly supporting said ring, and means for driving such roll.

21. The combination with a plurality of revolving rolls mounted on substantially stationary axes, of a revolving ring encircling 80 said rolls and engaging at its inner periphery the outer peripheries thereof, said ring movable transversely of its axis toward and from said rolls, and one of said rolls movable transversely of its axis toward and from the inner periphery of said ring, and means for driving 85 said ring, whereby by moving said movable roll against the face of said ring, its pressure thereagainst will be transmitted through the ring to the other roll, and means yieldingly pressing said movable roll against the ring. 90

22. The combination with a revolving ring 95 movable transversely of its axis, of a plurality of crushing-rolls revolving on substantially stationary axes at approximately equidistant points within the ring, said rolls encircled by the ring and engaging the inner periphery thereof, means for driving the ring, and means pressing one of said rolls yieldingly outwardly against the inner face of the ring, whereby such pressure from such roll is transmitted 100 through the ring to the other roll, and a crushing force is thus distributed between the rolls.

23. The combination with a revolving ring 105 movable laterally of its axis, of a plurality of crushing-rolls within and encircled by said ring, revolving on substantially stationary axes which are movable radially of the ring, means for driving one of said parts, and means for pressing one of said rolls radially 110 against the inner face of the ring, whereby the ring may move radially to distribute such pressure to the several rolls.

24. The combination with a revolving ring 115 movable laterally relatively to its axis, of a plurality of rolls within and encircled by said ring, revolving on substantially stationary axes and engaging the inner face of said ring, one of said rolls movable toward and from the others, means for driving one of said parts, 120 a casing surrounding said ring and permitting radial movement thereof, bearings carried by said casing for said rolls, and means for pressing said movable roll outwardly against said ring and away from the other 125 rolls, whereby said ring is free to move radially to distribute such pressure proportionately to all said rolls.

25. The combination with a revolving ring 130 movable radially, of a plurality of crushing-rolls within and encircled by said ring, revolving on substantially stationary axes

- spaced apart at predetermined distances, two of said rolls being movable transversely of their axes toward and from the inner face of the ring, means for driving one of said parts, 5 a casing surrounding said ring, bearings for said rolls in said casing, and springs reacting against said movable rolls and said casing for pressing said rolls outwardly against the inner face of said ring, whereby the pressure 10 of either of said movable rolls may be adjusted and said ring can move radially in said casing to adjust its position to proportionately distribute the pressure to said several rolls.
- 15 26. The combination with a revolving ring axially movable, of three crushing-rolls revolving on substantially stationary axes, movable laterally of the axis of the ring, said rolls encircled by and bearing against the inner pe-

riphery of said ring and holding the latter in 20 position, means for driving one of said parts, a casing surrounding said ring, movable bearings for said rolls, and springs reacting against said casing and said bearings for pressing the rolls outwardly against the ring, 25 whereby lack of uniformity in adjustment of the springs may be compensated for by radial movement of the ring, and thus the spring-pressure at each roll will automatically be proportioned.

30 In witness whereof I have hereunto signed my name in the presence of two subscribing witnesses.
